WASHING APPARATUS

Filed Oct. 12, 1925

UNITED STATES PATENT OFFICE.

HENRY L. TOWLER, OF MINNEAPOLIS, MINNESOTA.

WASHING APPARATUS.

Application filed October 12, 1925. Serial No. 61,869.

This invention relates to a washing machine or washing apparatus, and, particularly, to such an apparatus adapted to be used with any suitable receptacle, such as the laundry tubs now commonly supplied in nearly all dwellings. Commercial washing machines now used in large numbers, as a rule, have a frame and a receptacle supported thereon adapted to contain the liquid and clothes.

It is an object of this invention to provide an apparatus which can be mounted on a suitable receptacle, such as an ordinary domestic laundry tub in which the clothes to be washed and washing liquid may be placed and in which the clothes engaging means will operate.

It is also an object of the invention to provide an apparatus comprising a frame having adjustable means adapted to be clamped onto a suitable receptacle, such as a laundry tub, which frame carries a motor and mechanism operated thereby including cup carrying plungers adapted to be disposed in said receptacle and reciprocated therein.

It is another object of the invention to provide an apparatus comprising a frame including a casing closed except at its bottom, and in which a cross-head is reciprocated, to which are attached a plurality of plungers extending into said receptacle, the motor being mounted on said frame, and operating mechanism for reciprocating said crosshead, said receptacle being closed by a suitable cover.

It is still another object of the invention to provide an apparatus, as set forth in the preceding paragraph in which said casing forms a guideway for said crosshead and has its front side hinged to swing to open position whereby said crosshead may be removed.

It is also another object of the invention to provide a washing apparatus comprising a frame, members adjustable thereon to suit different lengths of tubs or receptacles and adjustable clamping means pivoted to said members adapted to fit tubs having walls of different thicknesses, said frame carrying a motor and suitable clothes-engaging members operated thereby.

These and other objects and advantages of the invention will be fully set forth in the following description made in connection with the accompanying drawings in which like reference characters refer to the same

parts throughout the different views, and in which

Fig. 1 is a view in front elevation of the device having a portion thereof removed and showing the receptacle and cover in vertical section;

Fig. 2 is a vertical section taken on the line 2-2 of Fig. 1;

Fig. 3 is a horizontal section taken on the line 3-3 of Fig. 1;

Fig. 4 is a partial view partly in side elevation and partly in vertical section of the crosshead and plunger connection thereto; and

Fig. 5 is a partial view in vertical section showing the connection of the motor shaft to the apparatus.

Referring to the drawings, an apparatus is shown comprising a frame member 6 having a flat bottom portion through which extend elongated slots 6^a and 6^b at each end, respectively, said bottom portion contacting the upper flat sides of members 7 and 8 by which it is secured by the headed screws 9 extending through the slots 6^a and 6^b into the members 7 and 8, respectively. The members 7 and 8 have spaced depending ears which are bored to receive a pivot shaft or pin 10 which also passes through spaced ears upstanding from members 11 forming one part of a clamp which has a flange 11^a at its lower portion extending at right angles and adapted to fit along the inside and over the top edge of a receptacle B. While any suitable receptacle may be used, the apparatus is designed particularly for use with the stationary laundry tubs now commonly supplied in the basement and other rooms of modern dwellings, the other member of said clamp, illustrated as 12, also having a flange 12^a extending at right angles and adapted to fit along the outside and over the top edge of receptacle B.

Headed bolts 13 extend through members 11 and 12 and are provided at the outer side of the latter member with wing nuts 14. Headed screws 15 also are threaded into the member 12 at its top and contact at their inner ends with the side of member 11. The frame 6 has a horizontal flange 6^c some distance above its bottom portion on one end of which is mounted a motor 16 illustrated as of the electrical type. Said motor has an armature shaft or driving shaft 16^a shown as movably coupled to a worm gear shaft 17. While any suitable coupling may be used, in the

embodiment of the invention illustrated, the end of shaft 17 is provided with a square bore 17^a into which loosely fits the squared end of the shaft 16^a. The worm gear shaft 17 is journaled in bearings 17 extending through holes in each end of a casing 6^d forming part of the frame 6, in which casing are disposed the worm gear 19 and the worm wheel gear 20. The bearings 18 have outer flanges 18^a preferably circular in shape, which are bolted to the ends of casing 6^d, said worm gear 19 being disposed between said bearings 18. Casing 6^d has a removable cover 6^e, at its rear side, held in place by suitable cap bolts and which has a hub thereon forming the rear bearing for a shaft 21, said casing having a boss 6^f therein forming the other bearing for shaft 21, worm wheel gear 20 being disposed between the bearing 6^f and the bearing in cover 6^e. It will be seen that frame 6 has a vertical flange or web 6^g which forms the rear side of a casing 6^h shown as of substantially rectangular shape and which is closed, except at the bottom portion thereof. The front side 6ⁱ of casing 6^h is formed as a hinged door having hinge lugs 6^m thereon co-operating with lugs 6ⁿ on one end of casing 6^h, lugs 6^m and 6ⁿ receiving the hinge pintles 22. The end of casing 6^h opposite that having the lugs 6ⁿ thereon has pairs of spaced lugs 6^k adjacent its top and bottom, through which pairs, respectively, extend headed studs 23 passing through eyelets in the eye-bolts 24 disposed between said lugs. The eyebolts 24 swing about studs 23 and into slots 6^p in one side of the front 6ⁱ of casing 6^h. Wing nuts 25 are provided for the eyebolts 24 and may be tightened to hold the front 6ⁱ in tightly closed position. The front, rear and end walls of the casing 6^h form a guideway in which is mounted for vertical reciprocation, a crosshead 26. Said crosshead has spaced rollers 27 revolvably mounted at its ends which bear against the ends of casing 6^h and said crosshead also has at each side and adjacent each end, pairs of rollers 28 which bear against the front and rear sides of casing 6^h. Crosshead 26 is thus effectively held in place and guided in its reciprocating movement. A crank member 29 is secured in the outer end of shaft 21 having an upper weighted or heavy counterweighted portion 29^a. Crank member 29 has an outwardly extending crank pin 29^b extending through the hub at the upper end of a pitman rod 30, which rod is connected at its lower end to the crosshead 26. Said crosshead has spaced webs 26^a at its lower central portion between which the lower end of pitman rod 30 is disposed, said webs having slightly projecting bosses through which a headed connecting pin 31 extends, said pin also passing through the hub at the lower end of pitman rod 30. Pin 31 is provided with a slot or recess in the rear of its head into 65 which is adapted to swing a locking key 32

pivoted on a pin 33 projecting from the front web 26^a.

The crosshead 26 is provided at each side with a bored chamber 26^b open at its lower end and into which end the upper end of 70 plungers 34 project, said plungers having secured at their lower ends, stems 35^a carrying vacuum cups 35 having concave lower faces and of the type commonly used in washing machines. Stems 35^a fit over plungers 34 and 75 are detachably held thereon by pin catches 41^a held in locking position by springs 41, forming releasing handles. The upper ends of the plungers 34 are slidable in chambers 26^b and coiled compression springs 36 are disposed between the upper ends of said plungers and the top of said chamber. Said plungers have secured in their upper ends, rods 37 extending through bores in the top of chamber 26^b and having collars 38 secured thereto 80 at some distance above the crosshead 26. Coiled compression springs 39 are disposed between the collars 38 and the top of crosshead 26. With this construction it will be seen that the plungers 34 are yieldingly connected to the crosshead 26. The receptacle B is closed by a cover 40 extending across the top thereof and supported at the sides and front of said receptacle as well as on the members 11. Said cover has slots 40^a in its rear side through which plungers 34 pass and in which may be disposed the water faucets for supplying water to the receptacle B.

In operation, when the apparatus is to be used for washing clothes the same will be 100 mounted on a suitable receptacle, such as a laundry tub, as shown in the drawings. Such laundry tubs vary in length and the members 7 and 8 can be adjusted on frame 6 by loosening the screws 9 so that members 11 will engage the inner side of the tub or receptacle. Screws 9 can then be tightened. The members 11 and 12 can now be firmly clamped on the receptacle or tub by tightening the nuts 14. The sides of said laundry tubs are often 105 at an angle and for this reason the screws 15 are provided. By turning this screw it will be seen that the flanges 11^a and 12^a can be made to stand at an angle to each other and to clamp therebetween the inner and outer surfaces of the tub. The bottom of frame 6 will 110 always stand horizontal, owing to the pivotal connection of members 7 and 8 with the members 11 and frame 6 will be held rigidly in stationary position. The cover 40 being in place, the motor 16 can now be started and worm gear 18 and worm wheel gear 20 will be rotated, thus revolving the crank member 29. This will reciprocate crosshead 26 and the plungers 34 will be reciprocated in receptacle 115 B. The clothes and washing liquid being placed in the receptacle the clothes will be engaged by the cups 35 and effectively washed. The plungers 34 can yield in their downward movement when the clothes are en- 120 125 130

gaged by compressing springs 36 and the upward movement of said plungers will be cushioned by the springs 39. The crosshead is guided for reciprocation in a vertical path 5 with the rollers 27 and 28 engaging the sides and ends of casing 6^h. The crosshead is effectively counterweighted by and compensated for by the heavy portions 29^a on the crank member 29. If it is desired to detach 10 the crosshead and attached parts, this can readily be done by loosening the wing nuts 25 and swinging the bolts 24 out of slots 6^p. The door 6^j can then be swung open about the pintles 22. When this door is open the crosshead 15 can be removed with the plungers by sliding pitman 30 off of pin 29^b. Pin 31 can also be quickly removed by releasing the locking key 32, and the crosshead disengaged from the pitman 30. Stems 35^a with vacuum cups 35 20 can be quickly detached by pressing spring handle 41 outward to move pin 41^a from engagement with plunger 34. It is frequently desirable to remove stems 35^a and cups 35 to manipulate the clothes. Access may readily 25 be had to the worm gear casing by removal of cover 6^e. It is thus seen that all parts of the device are very readily accessible and easily removable.

From the above description it is seen that 30 applicant has provided a very simple and efficient apparatus which can readily be mounted on any suitable receptacle, such as a stationary laundry tub and form, with such receptacle, a washing machine. Hot and cold 35 water faucets are usually provided adjacent the stationary laundry tubs and it will thus be quite convenient to supply the receptacle with necessary water. The device comprises comparatively few parts and is largely made 40 of light metal, such as aluminum, so that it can be easily handled and quickly mounted in position. When mounted on a tub or other receptacle, a simple and efficient washing machine is provided, one which operates with 45 little or no vibration. The device has been demonstrated in actual practice and found to be very successful and efficient.

It will, of course, be understood, that various changes may be made in the form, details, arrangement and proportions of the 50 parts without departing from the scope of applicant's invention, which, generally stated, consists in a device capable of carrying out the objects above set forth, in the 55 novel parts and combinations of parts disclosed and defined in the appended claims.

What is claimed is:

1. A device of the class described having in combination, a frame comprising a casing, 60 said casing having spaced guides in which a plunger-carrying crosshead is adapted to be reciprocated, said casing having a hinged front forming the outer side of said guides whereby said crosshead may be removed 65 when said front is in open position.

2. A device of the class described having in combination, a frame adapted to receive reciprocating plungers, an adjustable means at each end of said frame for engaging a receptacle and supporting said frame thereon, 70 members rigidly carried by said frame respectively pivoted to said adjustable means, said members being horizontally movable longitudinally on said frame, and means for clamping said members to said frame in various positions. 75

3. A device of the class described having in combination, a frame comprising a casing, said casing including a compartment for a worm gear and worm wheel gear, a motor on 80 said frame connected to said worm gear, said casing including a second compartment having an open bottom and closed sides and top, said sides forming a guide way, one of said sides being hinged at one end to swing out 85 and expose said guideway, a shaft to which said worm wheel gear is secured, a crank member carried by said shaft and disposed in said second compartment, a crosshead movable in said second compartment and vertically mov- 90 able in said guideway, a pitman connecting said crank member and crosshead, and cup- carrying plungers connected to said cross- head reciprocatable through the bottom of 95 said second compartment.

4. A washing machine structure adapted to be attached to and to cooperate with an open top receptacle having in combination, a frame comprising a casing having a front compartment constructed and arranged to 100 form a guideway for a reciprocating plunger- carrying cross head and to enclose a crank and connecting member for said cross head, a second compartment in the rear of said first mentioned compartment having spaced 105 bosses in which a crank shaft is adapted to be journaled, said last mentioned compartment being arranged to house a worm and worm wheel, a shelf on said casing adapted to support a motor for driving said worm 110 and supporting means for said frame.

5. A device of the class described having in combination, a frame, said frame having a casing thereon closed save at its bottom adapted to receive a crosshead and having 115 rectangularly disposed guiding surfaces at each end thereof, the front of said casing being formed as a hinged door, and means for holding said front in closed position.

6. A washing machine device adapted for 120 attachment to an open-top receptacle having in combination, a frame member for supporting washing machine parts, adjustable means at each end of said frame for engaging opposite sides of said receptacle, and members 125 rigidly and adjustably carried by each end of said frame pivoted to said adjustable means whereby said frame is rigidly supported on said means.

7. The structure set forth in claim 6, said 130

last mentioned members being horizontally movable longitudinally of said frame whereby said means may be arranged to engage different sized receptacles, and means for holding said members in rigid relation to said frame.

8. A washing machine structure adapted for attachment to an open top receptacle having in combination, a frame member comprising a casing adapted to guide movable washing machine parts, which parts extend into said receptacle, said frame having flat surfaces at each end, members slidable on said frame and having flat surfaces engaging said surfaces, means for clamping said member to said frame in various positions, clamping means for engaging the sides of said receptacle at each end of said frame, pivotal connecting means connecting

said members and said clamping means, and adjustable means carried by said clamping means for preventing movement about said pivotal connecting means.

9. A washing machine structure having in combination, a frame, means on said frame adapted to be attached to an open-top receptacle, said frame comprising a casing formed as a rectangular guideway, a cross-head having spaced guiding means received in said guideway and adapted to move vertically therein and carry means adapted to co-operate with said receptacle, said frame having a portion formed thereon for supporting a motor, and a portion for enclosing a driving mechanism connecting said motor and cross-head.

In testimony whereof I affix my signature.
HENRY L. TOWLER.
